US0D1045854S

(12) **United States Design Patent** (10) **Patent No.:** **US D1,045,854 S**
(45) **Date of Patent:** **** Oct. 8, 2024**

(54) **DISPLAY DEVICE**

(71) Applicant: **LG DISPLAY CO., LTD.**, Seoul (KR)

(72) Inventors: **Jaewon Hwang**, Paju-si (KR); **Wonjun Lee**, Paju-si (KR); **Dongkyu Yoon**, Paju-si (KR); **Seyoung Kim**, Paju-si (KR); **Dongjin Jeong**, Paju-si (KR); **Jinwon Kim**, Paju-si (KR); **Youhong Cha**, Paju-si (KR); **Sungsu Ham**, Paju-si (KR); **Sangyeop Jeon**, Paju-si (KR)

(73) Assignee: **LG DISPLAY CO., LTD.**, Seoul (KR)

(**) Term: **15 Years**

(21) Appl. No.: **29/820,135**

(22) Filed: **Dec. 20, 2021**

(30) **Foreign Application Priority Data**

Jun. 21, 2021 (KR) 30-2021-0029410

(51) **LOC (14) Cl.** **14-03**

(52) **U.S. Cl.**

USPC **D14/126**; D14/239

(58) **Field of Classification Search**

USPC D14/300, 307, 336, 371, 373, 374, 375, D14/376, 377, 380, 381, 382, 432, 448, D14/449, 450, 451, 125, 126, 127, 128, D14/129, 133, 239, 299, 900, 901, 902; D21/324, 325, 326, 327, 328, 329, 331, D21/332, 333, 663, 668, 669, 694, 696, D21/697
